ATTORNEY

UNITED STATES PATENT OFFICE

129,576

DESIGN FOR A HEEL

Abraham Ausubel, New York, N. Y.

Application August 27, 1941, Serial No. 103,045

Term of patent 3½ years

To all whom it may concern:

Be it known that I, Abraham Ausubel, a citizen of the United States of America, residing in New York city, county of New York, and State of New York, have invented a new, original, and ornamental Design for a Heel, of which the following is a specification, reference being had to the accompanying drawing, forming part thereof,

Fig. 1 is a front perspective view of a heel showing my new design.

Fig. 2 is a rear elevational view thereof.

I claim:

The ornamental design for a heel, substantially as shown.

ABRAHAM AUSUBEL.
